J. A. BOEHRINGER

ELECTRIC WALL BRACKET PLATE OR SIMILAR ARTICLE

Filed Feb. 10, 1928

John A. Boehringer
INVENTOR

UNITED STATES PATENT OFFICE.

JOHN A. BOEHRINGER, OF SPRINGFIELD, NEW YORK, ASSIGNOR TO STAR CHANDELIER CO., INC., OF NEW YORK, N. Y., A CORPORATION OF NEW YORK.

DESIGN FOR AN ELECTRIC WALL-BRACKET PLATE OR SIMILAR ARTICLE.

Application filed February 10, 1928. Serial No. 25,343. Term of patent 3½ years.

To all whom it may concern:

Be it known that I, JOHN A. BOEHRINGER, a citizen of the United States, residing at 145-85 Aberdeen Street, Springfield, Long Island, in the county of Queens and State of New York, have invented a new, original, and ornamental Design for an Electric Wall-Bracket Plate or Similar Article, of which the following is a specification, reference be-

ing had to the accompanying drawing, forming part thereof.

The figure is a front view of an electric wall bracket plate or similar article showing my new design.

I claim:

The ornamental design for an electric wall bracket plate or similar article, as shown.

JOHN A. BOEHRINGER.
